Primary Examiner — George J Ulsh*Assistant Examiner* — Andrea Marie McKay(74) *Attorney, Agent, or Firm* — Dinsmore & Shohl LLP(57) **CLAIM**

The ornamental design for an air conditioning housing as shown and described.

DESCRIPTION

FIG. 1 is a top perspective view of an air conditioning housing;

FIG. 2 is a bottom perspective view thereof;

FIG. 3 is a back view thereof;

FIG. 4 is a front view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the air conditioning housing that form no part of the claimed design.
